REAR DERAILLEUR BODY

Lucien Charles Hippolyte Juy, Rue de la Breuchilliere,
Zone Industrielle Nord, 21003 Dijon, France

Filed Aug. 13, 1973, Ser. No. 387,810

Claims priority, application France Feb. 22, 1973

Term of patent 14 years

Int. Cl. D12—11

U.S. Cl. D12—124

FIG. 3

FIG. 1

FIG. 2

FIG. 5

FIG. 4

FIG. 6

FIG. 1 is a top plan view of a rear derailleur body showing my new design;

FIG. 2 is a front elevational view thereof;

FIG. 3 is a right end elevational view thereof;

FIG. 4 is a rear elevational view thereof;

FIG. 5 is a left end elevational view thereof;

FIG. 6 is a bottom plan view thereof; and

FIG. 7 is a bottom front perspective view thereof, it being understood that the chain guide roller has been shown in broken lines for illustrative purposes only.

I claim:

The ornamental design for a rear derailleur body, as shown and described.
